WATER SOFTENER

Filed Dec. 17, 1926

Atty.

UNITED STATES PATENT OFFICE

LEE G. DANIELS, OF ROCKFORD, ILLINOIS

WATER SOFTENER

Application filed December 17, 1926. Serial No. 155,385.

This invention relates to water softeners of the base exchange type and relates principally to those designed for domestic service and still more particularly the hand operated type, although certain features herein-
5 after referred to are applicable to water softeners of all kinds.

The more important objects of the invention are:

1. To provide a water softener of a simplified and cheaper construction which, furthermore, will give better service and meet practical requirements without the usual complicated and expensive equipment, the said softener having a novel type of distributing means to insure uniform water flow throughout the cross sectional area of the bed of water softening material. The means employed comprises a single pipe, in the case of small sized units, having slots therein so graduated in sizes and so disposed along one side of the pipe the length thereof that the water discharged therefrom is positively distributed evenly without the use of baffles and other expedients otherwise required.
2. To provide a distributor pipe, as just referred to, mounted in a novel way in the wall of the water softener tank so as to permit its easy removal and replacement for the purposes of inspection and cleaning periodically or to permit the substitution of a new one in the event that ever becomes necessary. In connection with this feature I have also provided a pointed closure for the end of the pipe which, upon insertion through the opening in the side wall of the tank, will clear a passageway through the gravel deposited in the bottom of the tank so that it is not at all difficult to replace the pipe.
3. To provide a water softener having means in the head space therein above the bed of water softening material to cause the water injected into the head space at the time of regeneration to have a swirling action so as to better to pick up and dissolve the salt or better to assimilate the brine for passage downwardly through the bed of water softening material.
4. To provide a connection with the waste pipe vent of a water softener, a muffler where-

by to deaden the noise incident to the rushing of the water during the salt wash.

The foregoing and other objects of the invention will be brought out in the course of the following detailed description having reference to one practical embodiment of my invention as shown in the accompanying drawings wherein—

Figure 1 is a front view partly in vertical cross section of a water softener embodying the features referred to above;

Figs. 2 and 3 are horizontal sections taken on the lines 2—2 and 3—3 of Fig. 1 looking in the directions indicated by the arrows;

Fig. 4 is an enlarged sectional detail of the distributor pipe;

Fig. 5 is an enlarged sectional detail of the mounting therefor;

Fig. 6 is an enlarged detail of the free end of the pipe showing the pointed closure thereon;

Fig. 7 is an enlarged sectional detail of the waste pipe muffler; and

Fig. 8 is a fragmentary enlarged vertical section through one side of the tank illustrating the novel construction thereof.

The same reference numerals are applied to corresponding parts throughout the views.

The softener comprises a tank 10 preferably of an improved construction and design, as hereinafter described, and containing a bed of zeolite mineral or other water softening material shown at 11 over a layer of gravel, indicated at 12. In the normal softening operation a pipe 13, hereinafter referred to as a distributor pipe, introduces hard water in the gravel bed for passage upwardly through the mineral for softening. The hard water is supplied through a pipe 14 having connection with the pipe 13 through a pipe 15 extending vertically alongside the tank 10. The softened water is discharged from the tank through a pipe 16 communicating with an elbow connection 17 disposed in the head space, indicated at 18, above the bed of water softening material in the top of the tank 10. The normal flow during the softening operation is indicated by short arrows: hard water enters at 14, flows through communicating ports in the valve 20

100

and passes downwardly through the pipe 15 and into the lower end of the tank for discharge from the pipe 13 beneath the bed of water softening material. The pipe 13, as will presently appear, distributes the water evenly throughout the cross-sectional area of the bed for uniform contact with the mineral, and the water in passing upwardly through the bed is softened and is supplied in 10 this condition to the service system when it leaves the tank by way of the elbow 17 and the pipe 16.

For the purpose of regenerating the softener, salt or brine is arranged to be injected 15 into the head space 18 through the neck 21. The latter has a cap 22 suitably clamped in place by the hand screw device 23. A pipe 25 provides communication between the pipe 14 and the elbow 17 when the valve 20 is 20 shifted by means of its hand lever 26 to a position approximately at right angles to that shown. The regeneration flow is indicated by the dot and dash arrows and is as follows: hard water entering the pipe 25 from the pipe 25 14 is discharged through the elbow 17 into the head space 18 above the mineral in the tank. The salt or brine is picked up and dissolved or assimilated for passage downwardly through the mineral whereby to permit the 30 chemical exchange, commonly termed "base-exchange" to occur so that the exhausted mineral is revived. The waste water leaves the tank through the pipe 13 and passes upwardly through the pipe 15 and through communicating ports in the valve 20 to be discharged 35 to the sewer through a waste pipe 27. Broadly speaking, no invention is claimed in the mere provision of means for introducing hard water at one end of the tank and for discharging soft water at the other end, or in 40 means for controlling the direction of water flow so as to carry brine or dissolved salt through the mineral in the reverse direction from the softening flow and discharging the 45 waste water to the sewer. Such means, generally speaking, are well known in this art. However, invention is claimed in this case in the specific improved type of distributor pipe 13, in the location and disposition of the elbow connection 17, as well as in other details 50 to be described in full hereinafter.

The valve 20 is to form the subject matter of a separate application to be filed presently and it will, therefore, suffice for the present 55 purposes briefly to refer to the more important features thereof. It will be noted that the hand lever 26 has a pointer 28 thereon to indicate by reference to the legends on the plate 29 the position of the valve so that 60 the operator may readily control the operation of the softener. The position marked "1-Salt" is to indicate the place to which the pointer must be moved before salt or brine may be injected. At this position the 65 waste pipe 27 is in restricted communication

with the pipe 15 and immediately upon the removal of the cap 22 there will be a lowering of the water level in the tank down to the level of the horizontal pipe 30. The latter has a T connection, indicated at 31, furnishing an air vent to interrupt a siphon action when the level has dropped to this predetermined point. This leaves sufficient space in the tank so that salt or brine may be injected without resulting in flooding. The lid is then 70 replaced and, if the operator so desires, he may shift the valve to bring the pointer to the position marked "Off" in which position the tank is entirely shut off from communication with the supply pipe 14, the service pipe 80 16, and the waste pipe 27. The softener may be left this way over night to allow the salt or brine to settle down through the bed of softening material and thoroughly regenerate the same. This practice is followed only 85 where the mineral has been thoroughly exhausted and it is desired to insure its complete regeneration without having to use an exorbitant amount of salt or brine. Under ordinary conditions, however, where the mineral has become only partially exhausted the valve is shifted to the position marked "2-Wash" after the salt or brine has been injected. With the valve in this position the salt or brine is washed through the mineral 90 at a predetermined rate, the waste water being discharged through the pipe 27, as above described. The flow is continued 95 long enough to insure the using up of all of the salt or brine. The valve is then shifted 100 to the position marked "3-Soft" which corresponds to the normal softening operation. The purpose in having the positions marked 1 to 3 in the manner described is to make it easy 105 for the operator to put the softener through its operations by a count system in which he is not apt to make any mistake as to the sequence of operations. He commences with moving the valve to position 1, then to 2, and finally moves it back to 3 from which position 110 he started. When the valve is brought back to its normal position after the regeneration is completed it is usually a good practice to open a bib near the softener, as for example 115 in a laundry tub, long enough to allow all of the hard water in the head space in the softener tank to be flushed out instead of allowing this hard water to get into the service system. The adjustments indicated at 32 and 33, as will be described in the valve application, are provided to restrict the port openings in the valve 20 so that the rate of flow through the tank both during regeneration and during 120 softening may be accurately predetermined. The adjustment at 32 is made with a view 125 to allowing the brine to be washed through only at a rate at which a complete chemical exchange between the brine and the water softening material will properly occur. The adjustment at 33 is made with a view to pre- 130

venting the water passing through the mineral bed at a rate beyond that at which the same can be properly softened. In other words, these adjustments adapt the softener to the available water pressure in any particular community where the softening may be installed.

The distributor pipe 13, as shown in Figs. 1 and 3, extends diametrically across the inside of the tank near the bottom thereof. It is provided with transverse slots 34 on one side thereof in regularly spaced relation the length of the pipe. The slots are provided in two sets, the one set occurring in one quadrant of the cross-section of the pipe and the other set in the other quadrant, as appears in Fig. 4. The slots are also in staggered relation, as appears in Fig. 3, so that alternate slots occur in one quadrant while intermediate slots occur in the other quadrant. With this arrangement the water issuing from the slots is fanned out sidewise both ways with respect to the pipe toward the sides of the tank, as indicated by the dotted lines in Fig. 3. The slots are preferably graduated in size from the smallest at the ends to the largest at the middle of the pipe, as best appears in Fig. 3. This produces the heaviest discharge at the middle of the tank and a lighter discharge nearer the sides of the tank as the ends of the pipe are approached. The dotted lines indicate approximately the relative extent of the sprays at different points along the pipe. For convenience in manufacture the slots are all cut with the same sized blade but the depth of the cut, and consequently the length of the slot produced, is varied so as to have the smallest slots at the ends and the largest ones at the middle of the pipe. It will be apparent that substantially the same results may be produced by varying the size of the openings in other ways. With the present construction practically uniform distribution of the water flow throughout the cross-section of the bed is secured without the necessity of providing baffles or using other complicated and expensive means to secure the result desired.

I prefer to have the distributor pipe 13 easily removable and replaceable for the purposes of inspection and cleaning which may be found necessary at regular intervals depending on the amount of service rendered by the softener. The pipe 13 is, therefore, externally threaded, as shown at 35, for reception in the internally threaded end 36 of a bushing 37. The latter is externally threaded for reception in a plate 38 fastened about an opening 39 provided in the side wall of the tank. The bushing 37 provides communication between the pipe 13 and the pipe 15 by way of a connection 15' threading in the bushing as shown. Whenever the pipe is to be removed the connection 15' is

withdrawn and the bushing 37 is unthreaded so that the pipe may be pulled out from the side of the tank. It is then a simple matter to pass a saw blade of the like through each of the slots 34 to clear out any obstructions. The end of the pipe 13 is internally threaded for the reception of the externally threaded part 40 of a pointed plug or other closure 41. The latter has facets at 42 whereby the same may be threaded into the pipe or removed therefrom with a wrench. The pointed plug facilitates the entering of the pipe 13 into the tank as it serves to clear a passageway through the gravel bed. It will be apparent that the individual owner of the softener can easily attend to the matter of cleaning the distributor pipe as no special mechanical skill is required. In the replacing of the pipe a precaution must be taken to insure that the slots 34 will be moved to the under side of the pipe and for this reason the bushing 37 may be provided with a suitable bench mark the position of which will indicate when the slots are directed downwardly.

The elbow connection 17, as appears in Fig. 2, is preferably disposed approximately at right angles to the radius of the tank so that the water discharged therefrom during regeneration will be directed tangentially along the inside wall of the tank to give a swirling motion to the water in the head space. In this way the salt will be readily picked up and dissolved and there will be no danger of some of the salt remaining on top of the mineral bed which should have been washed down therethrough during the salt wash.

During regeneration I have found that with an ordinary vent pipe there is a certain amount of noise caused by the rushing of the water and for this reason I prefer to provide a muffler consisting of a lateral connection 43 with the T fitting 31, previously referred to, having an elbow connection with a short stand pipe 44, as shown in Fig. 7. The latter is in open communication with the atmosphere and a certain level of water will be maintained therein during the regeneration flow. Thus, the rushing of the water through the T fitting 31 will not cause any perceptible noise. Such noise would, however, be caused if the stand pipe 44 were placed directly on the T-fitting 31 and rising therefrom as in that case the rushing water would pass by the lower end of the open pipe and produce either a gurgling noise or more or less of a roar depending on the rate of flow. It will thus appear that by a very simple expedient I have avoided the annoyance referred to and the softener is better suited for domestic use. Softener tanks have, in the past, been short lived by reason of the corrosive action of the water and especially of the brine. I, therefore, prefer to construct the tank, as shown

in Fig. 8, of a shell 45 of sheet iron or other suitable material having the requisite strength and rigidity to sustain the weight of the bed of softening material as well as to withstand the water pressure active therein, the shell being provided with a lining 46 of another material which resists the corrosive action of the water and brine. The lining may be made of sheet copper or may be provided by spraying a coating of copper onto the inside wall of the shell, this latter process being commercially practicable. In actual practice it is preferred to use sheet copper for the lining 46 of the shell and to spray a copper coating on the end closure pieces 47, as indicated at 48. The end closure pieces 47 are of sheet iron or similar material provided to fit within the shell 45. The pieces 47 have annular flanges 49 which are arranged to fit snugly within the shell 45 inside the lining 46 thereof and having the lining 48 enveloping the same so as to cover the outside as well as the inside substantially as shown. When the parts are placed together the joints therebetween are sealed circumferentially of the end pieces, as shown at 50, preferably by brazing the shell with the end pieces. This will result also in a bond between the lining 48 and the lining 46. The lining 46 is swedged out to cover the sides of the opening 39, as indicated at 51 in Fig. 5, and is flared out on the outside wall of the shell, as at 52, behind the plate 38. The latter is preferably brazed to the shell, as indicated at 53. The completed tank structure is thus lined throughout with copper and will give much longer service than was heretofore secured with the ordinary iron tank constructions. It will also be noted that the bottom closure piece 47 is set in slightly within the shell 45 so as to provide an annular apron-like flange 54 to which the legs 55 may be riveted or otherwise secured to provide a base for mounting the tank.

It is believed the foregoing description conveys a clear understanding of my invention and all of its objects and advantages. It will be apparent that the invention is not to be limited in its application to the particular details above described as the embodiment herein shown and described has been selected merely for the purposes of illustration. The appended claims are, therefore, to be construed to cover all legitimate modifications, adaptations and variations of the invention as will no doubt occur to any one skilled in this art.

I claim:

1. In a water softener, the combination of a tank for a bed of water softening material, said tank providing a head space therein over the material for the reception of salt or brine for regeneration, pipe connections with the upper and lower ends of said tank whereby in normal operation to admit hard water to

one end of said tank and discharge soft water from the other end thereof, and a removable closure for a filler opening provided in the upper end of said tank arranged when removed to permit the introduction of salt or brine into the head space over the material in said tank, the upper pipe connection being arranged for directing the incoming water tangentially along the inside wall of said tank in said head space, whereby to produce a swirling motion of the water and thus insure the immediate picking up of the salt or brine and the carrying thereof downwardly through the material.

2. A water softener structure as set forth in claim 1, wherein the tank is substantially circular in transverse section, and wherein the upper pipe connection, for the purpose set forth, has an elbow communicating therewith and disposed alongside the wall of said tank in the head space therein with its discharge end directed approximately at right angles to the radius of said tank.

3. In a water softener comprising a tank containing a bed of water softening material with a layer of gravel or equivalent coarser material provided beneath said bed, and pipe connections for the upper and lower ends of said tank arranged to admit hard water to one end and withdraw soft water from the other end in normal operation, the lower connection comprising a pipe arranged to extend in a substantially radial direction from one side wall of said tank imbedded in the gravel beneath the bed of water softening material, said pipe having openings through the walls thereof whereby the pipe serves as a distributor pipe, a bushing threading on the outer end of said pipe and externally threaded for the mounting thereof in the side wall of said tank, said bushing being readily removable for removal and replacement of the pipe therewith, as for cleaning, and a closure for the inner end of said pipe, the same being pointed whereby to facilitate passage of the pipe through the gravel in the insertion thereof and also facilitate the accurate positioning thereof to permit threading of the bushing in the side wall of the tank when the pipe is inserted all way.

4. In a water softener, the combination with a tank substantially circular in transverse section and containing a bed of water softening material, and pipe connections with the upper and lower ends of said tank arranged in normal operation to admit hard water to one end of said tank and discharge soft water from the other end thereof, of an inlet pipe arranged within said tank in communication with one of said connections and extending substantially diametrically across the inside of the tank, said pipe having transverse slots cut through the walls thereof only on one side, there being two sets of slots one set being cut through one quadrant of

the cross section of the pipe and the other set being cut through the adjoining quadrant, the slots being spaced lengthwise of the pipe and being in staggered relationship so that alternate slots occur in one quadrant and intermediate slots in the other quadrant, and the slots being of gradually increasing size from the ends of the pipe toward the middle thereof for the purpose described.

5. In a water softener, the combination with a tank substantially circular in transverse section and containing a bed of water softening material, and pipe connections with the upper and lower ends of said tank arranged in normal operation to admit hard water to one end of said tank and discharge soft water from the other end thereof, of an inlet pipe arranged within said tank in communication with one of said connections and 15 extending substantially diametrically across the inside of the tank, said pipe having openings therein spaced lengthwise thereof, the openings at both ends being smaller than the openings at the middle of the pipe.

20 6. In a water softener, the combination with a tank substantially circular in transverse section and containing a bed of water softening material, and pipe connections with the upper and lower ends of said tank arranged in normal operation to admit hard water to one end of said tank and discharge soft water from the other end thereof, of an inlet pipe arranged within said tank in communication with one of said connections and 25 extending substantially diametrically across the inside of the tank, said pipe having openings therein spaced lengthwise thereof, the openings at the ends being smaller than the openings at the middle of the pipe and being graduated in size from the smallest to the 30 largest sized openings.

35 7. In a water softener, the combination with a tank containing a bed of water softening material, and pipe connections for the opposite ends of said tank for admitting hard water at one end and discharging soft water at the other end in the normal softening operation, one of said connections being arranged during regeneration to serve as a 40 salt wash inlet and the other as a waste outlet for said tank, of a waste pipe arranged to communicate with said last mentioned connection to conduct the waste from said softener, said waste pipe have a vent opening 45 therein whereby to predetermine the lowering of the water level in said tank when the same is to be charged with salt or brine for 50 regeneration, and a muffler communicating with said vent opening to deaden the noise 55 with incident to the regeneration flow.

60 8. In a water softener, the combination in a tank for a bed of water softening material, said tank providing a head space therein over the material for the reception of salt or brine 65 for regeneration, of pipe connections with

the upper and lower ends of said tank whereby in normal operation to admit hard water to one end of said tank and discharge soft water from the other end thereof and whereby during regeneration to admit hard water 70 to the head space to carry the brine therein down through the softening material, an elbow communicating with the upper pipe connection within the tank alongside the wall thereof in the head space with its discharge 75 end directed approximately at right angles to the radius of said tank to cause the water issuing therefrom during regenerating to produce a swirling action whereby better to pick up the salt or brine for passage downwardly through the softening material, and a transverse pipe within the lower portion of said tank communicating with the lower pipe connection, said pipe having openings 80 in the lower side thereof arranged during regeneration to receive the downcoming water and brine for discharge from the tank.

9. A water softener as set forth in claim 7 wherein the muffler comprises a laterally projecting pipe communicating with the waste pipe, and a stand pipe communicating at its lower end with the lateral pipe and open to the atmosphere at the upper end thereof.

95 10. In a water softener, the combination with a tank substantially circular in transverse section and containing a bed of water softening material and pipe connections with the upper and lower ends of said tank arranged in normal operation to admit hard water to one end of said tank and discharge soft water from the other end thereof, of an inlet pipe arranged within said tank in communication with one of said connections and extending substantially diametrically across 100 the inside of the tank, said pipe having transverse slots cut through the walls thereof only on one side, there being two sets of slots one set being cut through one quadrant of the cross section of the pipe and the other set being cut through the adjoining quadrant, and the slots at the middle of the pipe being cut deeper than the slots at either end of the pipe for the purpose described.

110 In witness of the foregoing I affix my signature.

LEE G. DANIELS.
